UNITED STATES PATENT OFFICE.

DANIEL F. SULLIVAN, OF LOWELL, MASSACHUSETTS.

STRIPING DEVICE FOR KNITTING-MACHINES.

No. 851,042.

Specification of Letters Patent.

Patented April 23, 1907.

Application filed November 20, 1906. Serial No. 344,324.

To all whom it may concern:

Be it known that I, DANIEL F. SULLIVAN, a citizen of the United States, residing at Lowell, in the county of Middlesex and Commonwealth of Massachusetts, have invented a certain new and useful Improvement in Striping Devices for Knitting-Machines, of which the following is a specification.

This invention relates to striping devices for knitting-machines, more specifically to striping attachments for circular spring-needle knitting-machines, and comprises improved mechanism for guiding, cutting, holding and releasing the yarns to change the stripe; means for adjusting the amount of opening of the yarn chopper or cutter and of the yarn-holder; means of varying the time of opening said cutter and holder to receive and release yarn with reference to the time of movement of the movable yarn-guides; means for independently adjusting said yarn-guides to bring the yarns to the proper height on the stitch-wheel or loop-wheel; double yarn-guides for so-called "plaited work," and other devices and combinations hereinafter described and claimed.

The terms "yarn-guide" and "yarn-guides" herein used without other qualifications will be understood to refer to the movable yarn-guide tubes, the fixed yarn-guide being designated as the "outside" yarn-guide.

The present invention is an improvement in some respects on the invention shown and described in reissued Letters Patent No. 35 12,251, dated July 26, 1904, granted to my assignee, and enables me to dispense with the locking-levers therein shown for the purpose of holding the yarn-guides from movement at certain times, intermediate swinging cams 40 which therein operate the yarn-guide levers, and the inside yarn-guide.

In the accompanying drawings, on two sheets, Figure 1 is a plan of my improvement with parts of a circular spring-needle knitting-machine; Fig. 2, a side elevation of a double yarn-guide in operative position and a loop-wheel; Fig. 3, an elevation of the inner end of the outside yarn-guide; Fig. 4, a side elevation of the pattern-wheel, yarn-guides, loop-wheel, and a portion of the head or cylinder; Fig. 5, an elevation of the yarn-cutting devices open; Fig. 6, a perspective view of the yarn-cutting devices closed.

A indicates a needle-cylinder. a a row of

spring-needles, B a loop-wheel or stitch-wheel, C a dividing-wheel, G a push-back, these parts being all of the usual construction and operation, the cylinder A being rotated by any usual means in the direction shown by the arrow thereon, which is the opposite direction from that in which the cylinder in said patent is represented as rotating and the wheels B C being driven by engagement with the needles a. In practice such other well-known devices as pressers, landing-wheels, and finishing-wheels as are generally used with circular spring-needle knitting-machines may be employed; but these form no part of my invention. The parts of the striping devices hereinafter described are supported on a stand E, as in said patent.

The pattern wheel or disk F does not differ essentially from that shown in said reissued patent, except that in each of the concentric circles of holes f³ f⁵ there are in the present invention twice as many holes as there are teeth in the ratchet f⁴ on the periphery of said wheel instead of the same number of holes as teeth.

In the circle of holes f⁵ which receive the pattern pins or screws f' f'' the additional hole for each tooth is used to receive another pin or screw f' or f'', these screws or pins being substantially as shown in said patent, but acting on the levers D D', which move the tubular yarn-guides d d' d¹¹ into and out of operative position directly instead of through the medium of the swinging cams shown in said patent. The levers D D' are provided with cams d² d³, against which the pattern-screws f' f'' strike to throw the yarn-guides out of operation, said levers being moved to operative position by springs d¹² d¹³ substantially like those shown in said patent.

When one of the yarn-guides is to be out of operation for only one course, a single pattern-screw f f' is sufficient, as shown in Fig. 4, because said pattern-screw will remain in contact with the corresponding guide-lever during one revolution of the cylinder A; but where several courses of the same yarn are required in the pattern the inoperative yarn-guide lever would, if only one pattern-screw were used to a course, move toward its operative position at the next course, to be immediately moved in the opposite direction by the next pattern-screw, and said lever would be in a constant vibration without any useful

result, because the outward movement would cause the joining at each revolution and then move inward without completing a course.

The use of an increased number of screws 5 renders unnecessary the locking-levers and connected parts shown in said reissued patent, reducing the first cost of the machine, the cost of repairs, and complication of parts.

The yarn-guides d d' in this invention are, 10 independently of each other, adjustable with reference to the loop-wheel and to the yarn holding and cutting device to enable the yarn delivered by the yarn-guide farthest from the loop-wheel to enter between the same needles 15 when thrown into operative position as the yarn delivered by the other yarn-guide, so that the length of the joining would be the same no matter which yarn-guide introduces the new yarn. To this end the yarn-guides 20 d d' are supported in and longitudinally adjustable in brackets d^4 d^5 , in which said guides are held by set-screws d^6 d^7 near the upper ends of said brackets, and the lower ends of said brackets are pivoted on the upper ends 25 of the levers D D' . The outer upper end portions of the tubes pass freely through loops d^8 d^9 , provided with hubs d^{14} d^{15} , which are supported on a horizontal stud d^{10} , which projects from an arm, secured on the frame or 30 stand E , and said loops are (independently of each other) capable of turning on said stud and are held on said stud by set-screws d^{16} d^{17} in an obvious manner. By setting said loops d^8 d^9 in different radial positions on the stud 35 d^{10} the height of the delivery ends of the yarn-guides d d' when at rest—that is, when in or out of operation—will be varied. Another short yarn-guide d^{11} is shown secured by a bracket d^{18} to one, d' , of the yarn-guides, 40 one above the other, to enable two yarns to be introduced together, these yarns being of different colors or material, or both, one of the yarns usually, but not necessarily, being heavier than the other, and one yarn showing on 45 the face and the other on the back of the fabric, the tubes being adjustable lengthwise to bring the delivery ends in the proper relation to each other, to the needles, to the loop-wheel, and to the holder and chopper N to 50 vary the height of the yarn on the loop-wheel, the upper yarn on the loop-wheel showing mostly on the back of the fabric and the lower yarn predominating on the face of the fabric, making what is called "plaited" work on the 55 stripe, which is formed by the double guide d d^{11} —that is, the plaited stripe will show a mixture of colors of which one is more apparent on the face and the other on the back of the fabric. Of course both stripes may be 60 plaited, if desired, by making both of the yarn-guides with double tubes, but in the drawings, Figs. 1 and 3, one yarn-tube is shown as single and would make a stripe of solid color. The yarn-severing devices are represented as comprising a block or anvil M , sup- 65

ported upon a post g on the push-back G and retained thereon by a set-screw m . The anvil M is arranged inside of a circle of needles a little above the tops of the same and back of the loop-wheel in the direction of rotation of the needle-cylinder. The cutter proper or chopper N is a wedged-shaped or ax-like blade having a cutting edge n , which conforms to the upper surface of the anvil M , said surface being represented as straight, 75 but downwardly inclined, and said chopper being secured rigidly to an arm or lever n' , pivoted at n^2 to the side of the anvil. The blade N is forced toward the anvil by a spring n^3 , secured to the anvil M and pressing 80 on the top of the arm or lever n' . Said blade N is opened by one arm h of a shaft H , which is parallel with the axis of the pattern-wheel F and which extends under the movable arm n' of the cutter N and is raised by a pin h' , set 85 in one of the inner circle of holes in the pattern-wheel, running over an incline h^2 on another arm of said shaft H just at the time when the joining is completed.

The yarn-holder I is represented as a helical or spiral wire spring, one end of which is secured to the push-back and the other to said arm h of the lever H .

The yarn is drawn between the coils of the spring-holder I over the anvil M below the cutter N and to the dividing-wheel C when thrown out of operation just before it is cut, and the new yarn is drawn out of said holder before the old yarn enters said holder.

The stationary outside yarn-guide P has a 100 curved guiding edge p , which presses against the beards of the needles and descends in the direction of rotation of the cylinder to prevent the yarn which is going out of operation from getting under the beards of the needles 105 and to guide the yarn which is coming into operative position down between the needles into the proper place on the loop-wheel B . So far as above stated the stationary 110 guide P is essentially the same as shown in said patent. I have added to said guide P a separator p' , which is represented as a bent wire attached to the under side of the curved part of said guide P and near the curved edge p and above the other guide-wire p^2 , 115 which holds up the yarn delivered by the lower tube d' of the double yarn-guide and prevents it getting below the loop-wheel, the separator keeping the two yarns from said double yarn-guide apart and preventing 120 them from being twisted together and causing the yarn from the upper tube d^{11} to take a higher place on the loop-wheel and to appear on the wrong side or unfinished face, while the lower yarn appears on the face 125 proper of the fabric. The yarn from the single guide d is also supported on the top of the separator and under the guide-plate in the manner shown in said patent.

The separator extends over the tops of the 130

needles and is always between the two yarns carried by the double tube-guide whether in or out of operation.

I claim as my invention—

5 1. The combination of needles, a loop-wheel, a cutter and a holder consisting of a closed helical spring, and means for opening said cutter and for stretching said spring-holder simultaneously with the engagement 10 of the yarn by the loop-wheel.

2. The combination of a pattern-wheel having pins, cam-levers, brackets pivoted to said levers, yarn-guides secured to said brackets, loops loosely surrounding said 15 yarn-guide above said brackets, and means for adjusting said loops independently of each other.

3. The combination of a needle-cylinder and needles, a loop-wheel, a movable double 20 yarn-guide, means for throwing the same into and out of operative position, a stationary yarn-guide adapted to direct the yarns into said loop-wheel and a separator to keep the two yarns delivered by said double yarn-guide apart from each other and one above 25 the other on said loop-wheel.

4. The combination of a needle-cylinder and needles, a loop-wheel, a movable double 30 yarn-guide, means for throwing the same into and out of operative position, a stationary yarn-guide adapted to direct the yarns

into said loop-wheel a separator to keep the two yarns delivered by said double yarn-guide apart from each other and one above the other on said loop-wheel, said separator 35 consisting of a wire supported by said stationary guide and extending from said stationary guide nearly to said double guide and having a free end portion which extends over the tops of the needles and to the inside 40 of the circle of needles and between the yarns delivered by said double guide.

5. In a striping attachment for circular-knitting machines the combination of a block having a face adapted to support a 45 yarn, a pivoted cutter having an edge parallel with said block when resting thereon, a spring to force said edge against said face of said block, a spiral wire spring yarn-holder, 50 movable yarn-guides to place yarns upon said face and means to raise said cutter away from said block, and to stretch said spring and separate said coils to receive one or more yarns and to release a yarn or yarns previously held by said holder.

In testimony whereof I have affixed my signature in presence of two witnesses,

DANIEL F. SULLIVAN.
